UNITED STATES PATENT OFFICE.

CHARLES KOZESNIK, OF NEW YORK, N. Y.

THIRD-RAIL ELECTRIC-RAILWAY SYSTEM.

No. 883,099.

Specification of Letters Patent.

Patented May 19, 1908.

Application filed October 30, 1906. Serial No. 341,251.

To all whom it may concern:

Be it known that I, CHARLES KOZESNIK, a citizen of the United States, and residing at New York, in the county of New York and State of New York, have invented certain new and useful Improvements in Third-Rail Electric-Railway Systems, of which the following is a specification, such as will enable those skilled in the art to which it appertains 10 to make and use the same.

This invention relates to third rail electric railway systems, and particularly to elevated railways of this class, and the object thereof is to provide an improvement in this class of 15 railways in which the third rail or conductor, in connection with which the contact shoes or devices of the cars or motors operate, is composed of separate sections which are in circuit only when the contact shoes or devices of the cars or motors are bearing thereon; a further object being to provide improved contact shoes or devices for the cars or motors in electric railway systems of this 20 class and also improved means for making electrical connection between the separate sections of the third rail and the main wire or conductor; and with these and other objects in view the invention consists in the construction, combination and arrangement of 25 the parts hereinafter described and particularly pointed out in the claims appended hereto.

This invention is an improvement on that described and claimed by me in a prior application filed June 16, 1904, Serial No. 212,770 and is fully disclosed in the following specification, of which the accompanying drawing forms a part, in which the separate parts of my improvement are designated by suitable 40 reference characters in each of the views, and in which:—

Figure 1 a sectional side view of separate sections of a third rail of an electric railway system and showing one of the car or motor shoes or contact devices in connection with one of said sections, together with the circuit forming and closing devices used in connection with said sections; Fig. 2 a sectional view showing one of the contact devices or 45 shoes which I employ, its supports and its circuit wire connections; Fig. 3 a view similar to Fig. 2 but showing a modification; and, Fig. 4 a sectional view showing the method of connecting the separate parts of the 50 separate sections of the third rail, said rail being

composed of top and bottom members as shown in Fig. 2.

In the drawing forming part of this specification, I have shown at *a* the sleepers or supports of the third rail *b* which is composed of separate sections *b*², and the said third rail or the separate sections thereof are hollow and composed of top and bottom members, the bottom members *c* being box-shaped in cross section, and said bottom 60 members are secured to the sleepers or supports *a* and the said separate sections of the third rail including the top parts *b*² and bottom members *c* extend the full length of the track, the rails *s* of which are shown in Fig. 1. 70

The box-shaped bottom member *c* of the third rail, or the separate sections thereof, are provided with side members *c*² having laterally, downwardly, and outwardly directed flanges *c*³, and the top parts *b*² of said 75 third rail, or the separate sections thereof, are provided with depending and laterally directed flanges *b*³, and between the flanges *b*³ and *c*³ is placed insulating material *d*, said insulating material being composed of any 80 suitable substance that can be molded or cast such as glass, porcelain or a composition of shellac and mica, or any similar substance or composition. In casting this insulating material in position the separate sections of 85 the third rail are laid on their sides and the insulating material, in a liquid state is poured in between the flanges *b*³ and *c*³, and in this operation the separate parts of the separate sections of the rail are held in proper relative 90 position by being placed in a suitable box or frame, and the openings between the flanges *b*³ and *c*³ at the inner side of the rail are closed in any suitable way so as to afford a space or chamber between the flanges *b*³ and 95 *c*³ to receive the insulating material. The object of this construction is to form a close connection between the separate parts *b*² and *c* of the separate sections of the third rail and at the same time insulate one of said parts 100 from the other, and in practice the flanges *b*³ and *c*³ of the separate parts of the separate sections of the third rail are provided at their adjacent faces with tongues or projections *b*⁴ and *c*⁴ as shown in Fig. 4, by means of 105 which the insulating material *d* is securely locked between the flanges *b*³ and *c*³, and the separate parts of the separate sections of the third rail are thus securely locked together and insulated one from the other.

At regular intervals within the box-shaped members *c* of the separate sections of the third rail are placed armature supports *e* which rest on the bottom of the said box-shaped members *c* and are insulated therefrom as shown at *d*², and two of which are employed, in practice, in connection with each of the third rail sections, those shown being at the adjacent ends of said sections.

10 Each of the armature supports *e* consists of two pairs of uprights *e*² connected by a base plate *e*³ insulated from the bottom of the box-shaped members *c*, and the separate pairs of uprights *e*² range transversely of and beneath the top parts of the third rail sections, and are provided in their upper ends with notches or recesses *e*⁴ in which are placed armatures *e*⁵, which range longitudinally of the third rail sections and are vertically movable and provided with pins *e*⁶ which rest in the notches or recesses *e*⁴, and each of the armatures *e*⁵ is provided with contact points or devices *e*⁷ which are secured thereto and over each of which is placed a contact plate or device *e*⁸ which is secured to the bottom surface of the top part *b*² of the separate sections of the third rail.

The contact parts and devices *e*⁷ and *e*⁸ are preferably composed of brush carbon. I also form the additional armature devices *e*⁵ in two separate parts *e*⁹ connected by a base plate or strip *e*¹⁰ of some non-magnetic metal preferably of lowest specific gravity such as aluminum whereby the load which is to be lifted by the electro-magnetic shoe device will be a minimum, thus insuring to a certain extent the upward movement of both ends of the armatures at the same time, and thus avoiding a possible cramping tendency in the movement of said armatures.

40 The contact devices *e*⁷ carried by the armatures *e*⁵ are connected by a wire *f* running longitudinally of and within the separate parts of the third rail, and running parallel with the track and incased and supported in any desired manner is a main supply wire *f*² which is connected with the wires *f* by feed wires *f*³ provided with switches *f*⁴.

The contact shoes or devices connected with the car or motor and which operate in connection with the third rail are shown at *g*, and in practice each car or motor is provided with two of these shoes or devices, and these shoes or devices are supported in a vertical position, in the form of construction shown, and each is yoke-shaped in form in cross section and provided with a roller *g*² which constitutes the main contact device proper and which bears on the top part of the third rail or the sections thereof. Each of the contact shoes or devices *g* is also provided in the opposite sides thereof and in the opposite end portions thereof with a supplemental contact device *g*³ consisting of vertically arranged arms pivoted in corresponding vertically ar-

ranged recesses in the opposite side portions of said shoes or devices *g* and adapted to swing laterally, said arms being provided at their lower ends with contact heads *g*⁴ adapted to bear on the opposite sides of the top parts *b*² of the separate sections of the third rail. The arms *g*³ are pivoted at *g*⁵ and passing through each of said arms above and below its pivotal support is a headed pin or bolt *g*⁶, and a spring *g*⁷ is employed to force the upper end of said arms outwardly and a corresponding spring *g*⁸ to force the lower end thereof inwardly, and it will thus be seen that the arms *g*³ are adapted to swing laterally and that the bearing or contact heads *g*⁴ thereof will always be in contact with the opposite side portions of the third rail or the sections thereof, and said opposite side portions of the third rail are grooved longitudinally to receive the heads *g*⁴.

85 Connected with each contact shoe or device *g* is an electro-magnet *h* provided with a top plate *h*² having side lugs or projections *h*³ vertically movable in slots *h*⁴ formed in a depending casing *h*⁵ connected with a top plate *h*⁶ which may be secured to the car or motor in the usual or any preferred manner, and the top plate *h*² of the electro-magnet *h* is provided with a vertically arranged member *i* which passes through a transversely arranged guide *i*² in the casing *h*⁵ and around which is placed a spiral spring *i*³ which serves to hold the contact shoe or device *g* in a depressed position, while permitting of its vertical movement.

90 In practice the electro-magnets of the contact shoes or devices *g* of each car are placed in connection by means of wires *i*⁴ which are connected with a battery or batteries on the car, not shown, and the electro-magnets *h* of each car or motor are also provided with a wire *i*⁶, and these wires connect in the usual way with said battery or batteries. Each of the contact shoes or devices *g* of each car or motor is also provided with a stem *j* which extends up through the corresponding electro-magnet and with which is connected a motor wire *j*² which is connected in the usual way with the motor on the car.

100 It will be seen that the electro-magnets *h* are energized by the battery or batteries on the car only on starting, and after starting by the current from the third rail, and as the car or motor moves along the track and the contact shoes or devices *g* come in contact with the separate third rail sections, the armatures *e*⁵ beneath said third rail sections are picked up and assume the position shown at the left of Fig. 1, and the circuit is completed from the main wire *f*² through the contact devices *e*⁷, the separate sections of the third rail, the contact shoes or devices *g*, and the wires *j*² to the motor on the car, and it will thus be seen that the separate third rail sections are never in circuit except when the 110

contact shoes or devices *g* are resting thereon; and the said third rail sections are made entirely harmless and no injury is occasioned by coming in contact therewith.

5 It will be understood that the improvements herein described may be applied to third rail electric railway systems of any kind or class and to cars or motors of any form of construction and by my improvements, I 10 provide means whereby only that portion of the third rail over which the car or motor is passing is energized, and whereby better contact is made with the third rail and better circuit connections with said rail and the operation of the railway or system improved.

15 In Fig. 3, I have shown a modification, in which the contact shoe or device *g* is provided only with the wheel or roller *g*² which bears on the top surface of the third rail, and it will be understood that this form of contact shoe or device may be used instead of that shown 20 in Fig. 2, if desired.

Having fully described my invention, what I claim as new and desire to secure by Letters 25 Patent, is:—

1. In a third rail electric railway system, a hollow third rail divided into sections composed of upper and lower parts connected but insulated from each other, armature supports within said sections and having separate uprights, vertically movable armatures lying between said uprights and supported thereby longitudinally of the track, said armatures being composed of separate parts 30 connected by a plate of non-magnetic conducting material, and electrical connections for said armatures, said armatures being provided with a contact device of carbon and the top part of the third rail being provided 35 with corresponding contact devices.

2. In a third rail electric railway system, a hollow third rail divided into sections composed of upper and lower parts connected

but insulated from each other, armature supports within said sections and having separate 45 uprights provided with notches or recesses in their upper ends, armatures lying between said uprights and having pins resting in said notches or recesses, said armatures being composed of separate parts connected by a 50 plate of non-magnetic conducting material and electrical connections for said armatures.

3. In a third rail electric railway system, a hollow third rail divided into sections composed of top and bottom members connected but insulated from each other, armature supports within said sections and provided with separate uprights having notches or recesses, 55 said armatures being composed of separate 60 parts connected by a plate of non-magnetic conducting material, a carbon contact device connected with said plate, a corresponding contact device connected with the top part of the third rail, and electrical connections 65 for said armatures.

4. A hollow third rail for electric railways consisting of top and bottom portions provided with laterally directed side flanges separated by insulating material, said side 70 flanges and insulating material being interlocked.

5. A hollow third rail for electric railways consisting of top and bottom portions provided with laterally directed side flanges separated by insulating material, said side flanges and insulating material being interlocked by a dove-tail construction.

In testimony that I claim the foregoing as my invention I have signed my name in 80 presence of the subscribing witnesses this 27th day of October 1906.

CHARLES KOZESNIK.
